UNITED STATES PATENT OFFICE.

FRANK M. SNYDER, OF LA FAYETTE, INDIANA, ASSIGNOR TO THE PEERLESS WIRE GOODS COMPANY, OF LA FAYETTE, INDIANA, A CORPORATION OF INDIANA.

SUPPORTING-LEG FOR SUPERPOSING WIRE TRAYS.

1,396,148.

Specification of Letters Patent.

Patented Nov. 8, 1921.

Application filed April 25, 1921. Serial No. 464,474.

To all whom it may concern:

Be it known that I, FRANK M. SNYDER, a citizen of the United States, residing at La Fayette, in the county of Tippecanoe and State of Indiana, have invented a new and useful Supporting-Leg for Superposing Wire Trays, of which the following is a specification.

It is the object of my invention to superpose ordinary wire trays, such as letter trays, by a simple and inexpensive superposing device which can be applied to any wire tray and which holds the trays firmly in the desired relationship to each other.

15 The accompanying drawing illustrates my invention: Figure 1 is a perspective view of two wire trays one superposed on the other by my improved superposing legs; Fig. 2 is an enlarged detail of one of 20 the superposing legs, and a corner fragment of an upper tray carried by the superposing legs; and Fig. 3 is a perspective view of one of the corner pieces provided at each corner of a lower tray, for receiving 25 the lower end of a superposing leg.

The trays 10 and 11 are ordinary wire trays, such as the ordinary letter trays for use on desks, which trays it is frequently desired to superpose one upon the other to 30 make a multiple tray of any desired number of stories.

I superpose these trays by detachable wire legs 12, one at each corner, extending between each lower tray and the next higher tray. Each superposing leg 12 is made of two strands of wire twisted together to form an intermediate part 13 of considerable strength. At the lower end, the two strands of each leg are separated to form a fork 14, the prongs of which are detachably insertible into two vertical sockets 15 formed in a sheet-metal corner piece 16, which is clamped on each corner of each tray which may at any time be a lower tray, preferably being provided at each corner of all the trays so that they may be superposed in any order. These sheet-metal corner pieces 16 are clamped in place by being provided with ears 17 which are bent around the upper wire 18 of the tray on the two sides forming the corner and close to the corner itself, as is clear from Fig. 3. At the upper end of each detachable leg 12 the two strands thereof are separated to form two fingers 19 and 20, the

latter longer than the former. The finger 19 hooks obliquely over the two longitudinal and transverse wires 21 and 22 of the tray bottom which cross each other closest to the bottom corner of the tray and are bent 60 upward to be looped around the top wire 18 of such tray. The finger 20 extends obliquely beneath such crossing point of the wires 21 and 22, and projects to the next inward crossing point 23—the first 65 crossing inward from both wires 21 and 22—and is there provided with an upturned end 24 which may be sprung over such crossing 23. This sprung condition holds the leg 12 firmly in place with respect to 70 the upper tray 11. The prongs of the fork 14 are also slightly sprung where they project into the sockets 15, so that they grip such sockets 15. This makes a firm connection of the leg 12 with the lower 75 tray. By these firm connections of the legs 12 with both the upper tray and the lower tray, the two trays are held rigid with respect to each other, and it is even possible to lift the whole tier of trays by grasping 80 merely the upper one, as the connection is so firm that the lower trays will hang from those above. The connections of the legs to both the upper and lower trays are easily attachable and detachable, so that the tiers 85 of trays may be rearranged easily and quickly.

I claim as my invention:

1. In combination, two trays, superposing legs for interconnecting such trays, each of 90 said legs being provided with hooked portions for hooking obliquely over and under wire crossings at the corners of the upper tray and being provided at its lower end with two separated prongs, and double-socketed members attached to corners of the lower tray for receiving the prongs at the lower ends of said superposing legs.

2. A superposing leg for coöperating with other similar legs to superpose one 100 wire tray upon another, comprising two wires twisted together at an intermediate portion and separated at their ends, the lower separated ends being arranged as two prongs, and the upper separated ends being 105 arranged as hooks for hooking over and under two obliquely-related crossings of the bottom of the upper tray, in combination with a double-socketed member attached to a lower tray for receiving said two prongs. 110

3. A superposing leg for coöperating with other similar legs to superpose one wire tray upon another, comprising two wires twisted together at an intermediate portion and separated at their ends, the lower separated ends being arranged as hooks for hooking over and under two obliquely-related crossings of the bottom of the upper tray, in combination with a double-socketed member attached to a lower tray for receiving said two prongs, the upper hooked portion which hooks beneath a crossing in the tray

bottom being provided with a bent end which may be sprung over such crossing to hold the leg in place.

15

In witness whereof, I have hereunto set my hand at La Fayette, Indiana, this 19th day of April, A. D. one thousand nine hundred and twenty one.

FRANK M. SNYDER.
